UNITED STATES PATENT OFFICE.

LAMBERT J. BORDO, OF HILLSIDE, PENNSYLVANIA.

BOILER FEED-GOVERNOR.

1,150,013.

Specification of Letters Patent. Patented Aug. 17, 1915.

Application filed March 31, 1910. Serial No. 552,494.

To all whom it may concern:

Be it known that I, LAMBERT J. BORDO, a citizen of the United States of America, residing in Hillside, county of Montgomery, 5 State of Pennsylvania, have invented a certain new and useful Improvement in Boiler Feed-Governors, of which the following is a true and exact description, reference being had to the accompanying drawings, which 10 form a part hereof.

My present invention consists in an improved device for automatically governing the supply of feed water to steam generating boilers, and the general object of my invention is to provide an effective arrangement for the purpose specified, characterized by its comparative simplicity in construction and reliability in operation.

The various features of novelty which 20 characterize my invention are pointed out with particularity in the claims annexed to and forming a part of this specification. For a better understanding of the invention however, and the advantages possessed by 25 it, reference may be had to the accompanying drawings and descriptive matter in which I have illustrated and described forms in which the invention may be embodied.

30 Of the drawings: Figure 1, is an elevation, partly in section, showing a portion of a boiler and the boiler feed governing mechanism therefor. Fig. 2 is a diagrammatic plan view illustrating the use of the 35 invention where a battery of boilers are supplied with water from a single pump or a high pressure water supply system. Fig. 3 is a diagrammatic plan view illustrating the use of the invention where the governor 40 is employed to regulate the supply of steam from the boiler to a steam pump delivering water solely for the boiler to which the governor pertains. Fig. 4 is a partial elevation 45 taken at right angles to Fig. 1, showing a small portion only of the apparatus shown in Fig. 1. Fig. 5 is a side elevation, and Fig. 6 an end elevation of a portion of a governor mechanism differing in some respects from that shown in Figs. 1 to 4 inclusive.

In the drawings, and referring first to the construction shown by Figs. 1 and 4, A represents the shell of a steam generating boiler and B a closed tank located above the water

level of the boiler and, as shown, mounted 55 on top of the boiler proper. A pipe C connects the interior of the tank B, adjacent its lower end, with the interior of the boiler below the normal water level thereof. Similarly, a pipe C' connects the upper end of 60 the tank B to the boiler at the normal water level thereof. As shown, the pipes C and C' extend through the boiler shell at the top, down to the proper levels. Within the tank B is located a float in the form of a 65 cup D shown as closed at its upper end by the perforated cover D², and, as provided with a central sleeve through which extends a rod D' secured to the sleeve of the cup and to the cover by a pin D³. The lower end of 70 the rod D' is guided in a sleeve E held in a bracket B' rising from the bottom wall of the tank. The upper end D⁴ of the rod D' is fluted and enters a guiding sleeve F passing through and screwed into the upper 75 wall or cover B³ of the tank. The upper end of the sleeve F is closed except for an aperture through which extends a fine rod or small wire D⁵ secured to the upper end of the rod D' or rather to the extension D⁴ thereof. A stuffing box F', provided on the upper end of the sleeve member F, prevents 80 leakage along the member D⁵. Above the stuffing box F' an abutment is secured to the member D⁵. As shown this abutment 85 consists of an externally threaded split sleeve G which may be adjustably clamped in place by a nut G'. The abutment G is engaged on the underside by a yoke member H, the downturned ends H' of which are 90 engaged by the branches I' of a counterbalancing lever I fulcrumed on the bracket B' carried by the tank cover B³. I² represents a counterweight adjustably secured on the body of the lever I. Adjacent its lower end 95 the tank B is formed with an opening B² which is closed by the base of a valve casting L. The latter is formed with two chambers L' and L² to which are connected the pipes O and P. The chambers L' and 100 L² are connected by a valve seated port controlled by a valve member M. In operation, as hereinafter explained, the valve chamber L is always connected to the boiler either above or below the water level therein depending on the conditions of use. The valve M is balanced by means of a hollow piston extension M' which enters a cylinder

chamber formed in a member N threaded into the valve casing L and projecting into the chamber L'. Provision is made, as by the port M², for obtaining a leakage from the chamber L' into the interior of the hollow piston M' and of the cylinder in which the latter works. The valve M is operated by a stem or operating device K' which extends through a passage formed in the casting L into the tank B, where a reduced portion K' is straddled by the bifurcated end of an arm J² secured to a rock shaft J. Another arm J' secured to the rock shaft J, enters a recess or passage D⁶ formed in the lower end of the shaft D'.

In operation, the water level in the tank B rises above and falls to the level of the upper end of the pipe C accordingly as the lower end C' of the pipe is above the level of or is sealed by the water in the boiler. It is of course entirely obvious that when the water level of the boiler falls low enough to uncover the lower end of the pipe C', the water in the tank B above the connection to the pipe C will flow out under the action of gravity. When thereafter the water level in the boiler rises to cover the lower end of the pipe C', the tank B immediately begins to fill up with water, for the steam in the upper end of the tank B condenses with considerable rapidity and the boiler pressure forces water from the boiler into the tank to compensate for the diminishing volume of the steam. The counter balance for the float is so adjusted that the float rises and falls with the water level in the tank B. As the float rises and falls the valve M is moved toward and away from its seat through the connecting parts J, J', J² and K.

The float controlled valve L may be employed in different ways to govern the supply of water to the boiler in which the governor is applied. In Fig. 2 where a number of boilers A are supplied with water from a high pressure supply system which in the form shown comprises a pipe Q connected to the delivery side of a water pump R operated by a steam engine S. As shown in Fig. 2 the pipes P from the various governor controlled valves L are connected to the pipe Q and the pipes O are preferably connected to the corresponding boilers below the water levels therein. When the water level in any boiler A falls below the normal level the float in the corresponding governor tank B falls and opens the corresponding valve L thus allowing water to pass from the pipe Q to pipes P and O and valve L into the boiler. When the water level in the boiler rises to the proper height the valve L is automatically closed.

In Fig. 3 the pipe P from the governor valve L runs to the inlet side of the steam cylinder S operating the pump R employed

to pump water into the boiler through the pipe R' and the boiler level governor directly controls the operation of the pump. In this use of the invention the pipe O connects to the boiler A above the water level in the latter.

With either arrangement it will be observed that the boiler pressure is at all times admitted to the valve chamber L' and this is an important feature for on this account it is unnecessary to provide any stuffing box for the valve stem K' where the latter passes through the portion of the valve casing L from the chamber L' into the tank B. Preferably, the stem K' should substantially fill the passage L³, but with the conditions specified there is no need for a tight fit, since, with a loose fit, the leakage is practically negligible in amount since the pressure in the chamber L' and in the tank B are practically the same, each being substantially equal to the boiler pressure. Moreover any leakage which may occur is practically harmless. A leakage along the stem K', when the latter substantially fills the passage L³, is restricted also by the fact that this passage, as shown in Fig. 1, is below the normal low water level in the tank B. The avoidance of a stuffing box about the stem K' is important. It is an advantage of course to avoid the expense of a stuffing box and particularly to avoid the necessity for looking after a stuffing box in this location. In the second place a tight packing about the stem K' would greatly increase the frictional resistance to the operation of the governor and hence the omission of the stuffing box increases the effectiveness of the apparatus. The stuffing box F' about the fine rod or wire D⁵ does not offer an appreciable resistance to the operation of the device because of the small diameter of the part D⁵. The float is efficiently guided at top and bottom by the mechanism provided and in a manner which avoids any appreciable frictional resistance to the movement of the float. By making the float, as shown, of a thin cup of large volume filled with water, the specific gravity of the float is caused to approach quite closely to the specific gravity of the water, and this is an important factor in obtaining reliable operation, for since the weight of the float is formed largely by the water contained in the cup shaped member B the specific gravity of the float itself will vary with the specific gravity of the water in the tank upon changes in the temperature of the water consequent upon variations in the boiler pressure.

As a convenient means for indicating the conditions of the apparatus, I prefer to arrange an indicator at some convenient point, as adjacent the water column X, for the boiler level indicating glass or gage connections, and in Fig. 1, I have shown this in-

dicator in the form of a slide Y, provided with an indicator point Y' at its lower end, and mounted in a bracket X' secured to the upper end of the water column, and connected by a flexible cord W running from the pulleys W' to the end of the counterbalancing lever I.

Instead of the small counterbalancing lever arrangement shown in Figs. 1-4 inclusive, I can of course use other counterbalancing devices, and in Figs. 5 and 6 have shown the sleeve FA corresponding to the sleeve F of the first construction provided with trunnions F² and have replaced the yoke H by a block HA carrying trunnions H² and have provided springs U and U' which act between and tend to spread apart the trunnions H² and F². As shown, each of the springs U and U' is in the form of a helix with one end extended and hooked about the trunnion F² at one side of the apparatus and the other end extended and hooked about the trunnions H² at the other side of the apparatus. The particular spring arrangement shown is advantageous for as the springs expand in moving from the full line position shown in Fig. 5 into the position indicated by the dotted lines in that figure the decrease in tension of the springs which occurs is compensated for more or less by the more effective manner in which they exert their pressure. The spring arrangement is of course more advantageous than the counterbalancing lever arrangement under some conditions of use as for instance in marine service.

It will be readily apparent to those skilled in the art that the governor mechanism disclosed is effective and reliable and in particular is much more effective and reliable than governing mechanisms for the same purpose in which flexible diaphragms or hollow, air or gas filled floats liable to collapse are employed.

While in accordance with the provisions of the statutes I have herein illustrated and described the best forms of my invention now known to me, it will be apparent to those skilled in the art that changes may be made in the form of the apparatus disclosed without departing from the spirit of my invention and that certain features of the construction disclosed may be used with advantage under certain conditions without a corresponding use of other features of the invention.

Having now described my invention, what

I claim as new, and desire to secure by Letters Patent, is:

1. The combination, with a boiler, of a 60 governor controlling the supply of water thereto and comprising a structure formed with two valve chambers connected by a valve seated port, a tank chamber, and a passage leading away from one of said valve 65 chambers to the interior of the tank chamber, said tank chamber being located above the normal high water level line of said boiler, a connection between the last mentioned valve chamber and the boiler, a pipe 70 connection between the upper end of the tank chamber and the boiler at one level thereof, a pipe connection between the lower end of the tank chamber and the boiler at a level below that at which the first mentioned pipe is connected to the boiler, a float in said tank chamber, said last mentioned pipe connection opening to said tank chamber above the level at which said passage opens into said tank chamber, a balanced valve controlling said port and operating connections between the float and the valve, comprising a member extending through and loosely filling said passage.

2. The combination, with a boiler, of a 85 governor controlling the supply of water thereto, comprising a closed tank located above the normal high water level line of the boiler and formed with an opening in its wall, and a valve controlling the flow of feed 90 water to the boiler, said valve including a casing attached to the tank and closing said opening thereof and being formed with two valve chambers connected by a valve seated port and with an opening connecting one of 95 said chambers with the interior of said tank through said tank opening, a pipe connection between the last mentioned valve chamber and the boiler, a valve proper controlling said valve seated port, a float in said 100 tank, an operating connection between the float and the valve including a member extending through and loosely filling said valve casing opening, a pipe connection between the upper end of the tank and the 105 boiler at one level thereof, and a second pipe connection between the lower end of said tank and the boiler at a level of the latter below that at which the first mentioned pipe connection is connected to the boiler.

LAMBERT J. BORDO.
